UNITED STATES PATENT OFFICE.

JOSEPH ALVAH SCOTT, OF NEW YORK, N. Y., ASSIGNOR TO SCOTT ENGINE AND CONSTRUCTION COMPANY.

INTERNAL-COMBUSTION ENGINE.

991,029.

Specification of Letters Patent.

Patented May 2, 1911.

Application filed October 8, 1904, Serial No. 227,680. Renewed July 24, 1909. Serial No. 509,448.

To all whom it may concern:

Be it known that I, JOSEPH ALVAH SCOTT, a citizen of the United States, residing in New York city, New York, have invented 5 certain new and useful Improvements in Internal-Combustion Engines, of which the following is a specification.

This invention relates to the general class 10 of internal combustion or explosion engines, wherein an explosive charge is compressed and then ignited, whereupon it acts directly on the piston to drive it to the outer end of the cylinder. The engines of this class are single-acting, the piston being returned to 15 the inner end of the cylinder by means other than the direct impact of an explosion.

In order to make clear the peculiar cycle 20 of the engine of this application, it may be proper to state that in the ordinary four cycle internal combustion engine the ignited charge, by explosion, drives the piston to the outer end of the cylinder; the piston then returns and expels the products of the explosion (thus completing one revolution); 25 then moves again to the outer end of the cylinder, thus drawing in a fresh explosive charge, and finally moves back to the inner end of the cylinder and compresses the explosive charge preliminary to its ignition. 30 Thus the crank makes two revolutions between explosions.

In the engine embodying the present invention both ends of the cylinder are closed, but the engine is single acting. When the 35 charge is ignited the piston is driven to the outer end of the cylinder, but it finds a charge of air incarcerated in that end of the cylinder and this it compresses and forces out through valve-controlled outlets to and 40 through a carburetor, when the compressed air receives the necessary hydrocarbon or other combustible gas or vapor to form an explosive charge. The piston then returns to the inner end of the cylinder, expelling 45 the gases or products of the explosion. The compressed carbureted charge is admitted to the inner end of the cylinder at the moment the 50 gases are expelled and as the piston is about to start on its return stroke, and is ignited, thus driving the piston outward again. It will be seen that the charge is 55 fully compressed on the outstroke, and that there is an explosion at each outstroke of the piston. The exhaust of the products of

the explosion is effected at each instroke of 55 the piston. It will be noted also that the charge is admitted to the combustion chamber under full compression, the degree of compression and the quantity of the combustible mixed therewith being controllable. 60 In this manner the full charge for the explosion is provided each time without waste, and while the present engine is in substance a two-cycle engine, it is free from defective exhaust and supply of combustible 65 mixture.

The means for effecting the operations recited above constitute novel features of the invention, and other novel features reside in the starting means, the means for carbureting the charge of air under pressure, and other minor features which will be hereinafter described.

As shown in the accompanying drawings, 75 which illustrate an embodiment of the invention, two pairs of like engines are represented with their piston-rods coupled respectively to cranks in a common shaft, the outer ends of the cylinders being presented downward. But obviously the invention is 80 not limited to these features.

In the drawings Figure 1 is a side elevation of the group of four engines, parts at the left being in vertical section, and other parts broken away to better disclose the construction. Fig. 2 is a plan with parts in horizontal section. Fig. 3 is substantially an elevation of the side or end, seen at the right in Figs. 1 and 2. This view is on a larger scale than Figs. 1 and 2. Fig. 4 is a transverse vertical section taken at line α^4 of Fig. 2 and drawn to the same scale as Fig. 3. The plane of the section is substantially indicated by line α^4 in Fig. 2. Fig. 5 is a vertical sectional view of one of the engines 95 showing the valves and internal construction. Fig. 6 is a somewhat diagrammatic view illustrating the carbureting devices or means. Figs. 7 and 8 are views illustrating the reversing mechanism. Fig. 7 is a side elevation. Fig. 8 is a plan. Fig. 9 is a diagrammatic view of the electrical igniting devices. Fig. 10 includes a side view and end views of the shafts of the cam-operating levers.

In the general views, F designates a strong 105 frame, in which is rotatively mounted, below, a shaft S, having in it four cranks C, and above, four upright engines E, the pis-

tons of which are coupled, respectively, to said cranks through their rods in a known way. It may be explained that the engines are grouped in pairs, one at the left and the other at the right in the general views; that the engines of a pair have their cranks disposed oppositely, and the cranks of one pair are disposed at right angles to those of the other pair.

10 The more detailed description of the engine, its valves, and other adjacent parts, may be best understood by reference mainly to Fig. 5. In this figure, 1 designates the cylinder; 2 its jacket; 3 its piston, and 4 its piston-rod. The outer end of the cylinder is closed by a head 5, through which the piston-rod plays, being made tight by suitable means at 6. The air to be compressed in the chamber *a* at the outer end of the cylinder, 15 enters at an inlet 7, controlled by a valve 8, held closed by a spring 9; and after compression the air flows out to a conduit 10, the flow being controlled by the valve 11, held closed by spring 12. The conduit 10 is best 20 seen in Fig. 6, and the compressed air flows through this conduit to a carbureting device (which will be hereinafter described) from which the carbureted air or explosive mixture flows through a conduit 13, to an inlet- 25 chamber 14, (seen also in Fig. 5). From this inlet-chamber the mixture may flow to a supplementary combustion chamber 15, through an inlet controlled by a non-return valve 16, held to its seat by a spring 17. The 30 functions of this supplementary chamber 15 will be hereinafter explained. The chamber 15 communicates with an intermediate chamber 18, from which the mixture may flow 35 through an inlet controlled by a valve 19, 40 into the main combustion chamber 20 open to the inner end of the cylinder. The exhaust outlet 21, of the engine, is controlled by a valve 22, held to its seat by a spring 23. The valves 8, 19 and 22 are opened 45 positively by cams as will be described, and the valves 11 and 16 are in the nature of check- 50 valves or non-return valves. Between the valve 11 and the carbureter (Fig. 6) there is a non-return valve 24 in the conduit 10, which is provided at its back with a screw 25, so 55 that it may be closed or its opening be regulated in order that it may serve as a throttle. This valve prevents a blow-back, and also 60 prevents the compressed air from the cylinder from mixing with the combustible vapor or gases except as provided. It may be 65 stated here that 26 is the main igniter and 27 the supplementary igniter; these being both electrical sparking devices of a known kind. The supplementary combustion chamber 15 will ordinarily be filled with the explosive mixture under pressure, and on starting the engine the supplementary igniter 27 ignites this mixture. The ignited explosive 70 mixture expands into the main combustion

chamber and the upper end of the cylinder, opening and passing the valve 19, and by acting on the piston, sets the engine in motion. After being set in motion, the supplementary igniter is switched out and the engine afterward operates in the usual way, the ignition being effected in the main combustion chamber 20 by the igniter 26. It should be explained that the valve 19 is a balanced valve, having on its stem 28 a piston 29, of or about the same diameter as the valve and playing in a cylindrical chamber 30, above the chamber or conduit through which the explosive mixture flows to the valve 19. This chamber 30 is connected by 75 a small pipe 31 with the conduit 10, through which it is supplied with compressed air. The pipe 31 is shown somewhat diagrammatically, in Fig. 6, but it will be understood that the means and manner of making this 80 connection are not important. The pressure of the explosive mixture in the supplementary chamber 15 tends, of course, to open the valve 19, and this tendency is counteracted by the pressure on the piston 29 by the compressed air in the chamber 30, as well as by 85 any pressure in the combustion chamber 20. This pressure in the chamber 30 will ordinarily be slightly greater than the pressure of the explosive mixture tending to open the valve, and hence it obviates the liability of the valve being opened by the suction of the exhaust. When, however, there is an explosion in the chamber 15, the pressure is so 90 excessive as to readily open the valve and 95 permit the gases from the explosion to pass to the cylinder.

The carbureter shown in Fig. 6 comprises a tight, closed reservoir or holder 32, supplied with a volatile combustible liquid by 105 any suitable form of pump *P*, through a pipe *p*, and is provided with a float-valve 33 to limit the rise of the liquid therein. This holder has an outlet nozzle 34, the tip of which is directed upward and terminates at 110 about the high level of the liquid in the holder. This discharge nozzle is disposed in the contracted part of an injector-chamber 35, connected at its top with the conduit 13. The compressed air conduit 10 is connected with the lower part of the chamber 35 by a branch pipe 10^a and as the air rushes upward about the nozzle 34, the volatile combustible liquid is drawn out in spray or 115 vapor from the latter and mixes with the air. To facilitate the mixing, a foraminous, conical diaphragm 36 is fixed in the chamber above the nozzle 34. In order to facilitate variation in the proportions of the two ingredients in the mixture of air and combustible vapor or fluid, a branch pipe 10^b connects the pipe 10 with the upper part of the chamber 35; and in the respective branches 10^a and 10^b are dampers or cut-off cocks, 37, adapted to be operated in 120 125 130

unison by a connecting-rod 38 and lever 39. The dampers are so set that when one is full open the other will be closed. The branch 10^b supplies pure air to the conduit 13, and 5 through it, and the dampers, the proportion of air in the mixture may be regulated with sufficient exactness, or nicety. As the air is under pressure in the injector chamber 35, it is important that the reservoir 32 10 shall be connected at its top with the compressed air supply, and this is effected by a pipe 40, seen in Fig. 6. This balances or equalizes the pressure in the carbureting device. The pump P may be of any kind; 15 indeed it is not important to this invention how the vessel or reservoir 32 is supplied.

The electrical igniting devices will be understood from the diagram in Fig. 9. In this view, G designates a generator; A 20 an accumulator or storage battery; M a magnet for automatically cutting out the accumulator, and disposed in the generator circuit; M¹ a magnet for automatically cutting out the supplementary igniters 27 when the generator is set in motion by the starting of the engine; 26 are the main igniters; C¹ is the rotating controller which completes the circuit successively through the igniters of the four engines, and S¹ is the switch-device as a whole. The circuits will be traced: When the generator G is running (and this will be only when the engine is running) the current flows from the brush b, by wires c and W, to and through magnet M, and 35 thence back to the other brush b¹. The magnet M being excited attracts its armature a, thus putting the metal armature lever a^x into contact with a terminal t. A branch of the circuit flows by wire c¹ to and through the magnet M¹, thence to the wire W, and 40 thence back by W and c to the other brush b¹ of the generator. The magnet M¹ being thus excited, attracts its armature a¹, and through a rod r, coupled to its armature 45 lever a^{xx}, shifts the switch-arms s over from the contact terminals c¹, belonging to the supplementary igniters 27, to the terminals e of the main igniters 26. Another branch of the current flows from brush b of the generator 50 to the terminal t, thence to the armature lever a^x, and thence by wires c², to the several switch-arms s; thence by wires c³ to the several main igniters 26, thence, by wires c⁴, to the respective segments of controller C¹, and thence by wires c⁵, W, and c, back to the brush b¹. When the engine, or 55 engines, stop running, the generator G also stops. The magnets M and M¹ cease to be excited, and the springs s^x of the respective armature levers retract the latter. Thus, the igniting circuit is broken at t, and closed to the accumulator A, through the terminal t¹. At the same time the switch arms s are shifted to the contact terminals c¹, which 60 are connected with the respective segments

of the controller C¹ by wires c⁶, to the igniters 27, and wires c⁷ from the latter to the controllers. The current may flow from one pole of the accumulator by wire c⁸, lever a^x, and wires c⁹, to the switch-arms s, and thence to the igniters 27 and the controller, as explained. From the controller it flows by wires c¹⁰ and W back to the other pole of the accumulator. Consequently, when the engine is to be started up, the supplementary 70 igniters will be supplied from the accumulator until the engines are in motion and the generator provides a current; then the accumulator and supplementary igniters will be switched out automatically. The switch-shifting magnet M¹ is, of course, only a means of automatically operating the switch, and this may be done by hand through a knob k on the rod r. The other magnet 80 might also be dispensed with and the accumulator be switched in and out by hand. 85

It has been stated that some of the valves of the engine are operated by cams, and this feature will now be described briefly, promising that the mechanism herein employed for driving the cam-shafts has no special novel features, and any suitable mechanism may be employed for the purpose. It may also be explained that the valve-operating and reversing means shown herein forms no 90 part of the present invention and is embodied in a divisional application, Ser. No. 243,335. It is shown herein as forming a part of an operative structure but any other form of valve-operating and reversing means 95 may be employed in its stead.

Referring to Fig. 3, 41 is an upright shaft, driven from the main shaft S through ordinary spiral gears 42. Mounted rotatively in suitable bearings on the frame, and one above the other, are two cam-shafts, 43 and 44. The upper one 43, of these shafts is driven from the upright shaft 41 by ordinary spiral gears, inclosed in housings, and the shaft 43 drives the shaft 44 by spur gears, also housed. The speed of the shafts 105 43 and 44 is the same as that of the main engine shaft.

Referring to Figs. 7 and 8 which show the cams best; on the upper shaft 43 are, the cam 45, which opens the exhaust-valve 22, and the cam 46, which opens the balance valve 19, which admits the explosive charge to the cylinder. On the lower shaft is fixed the cam 47, which opens the air inlet-valve 8. It need only be said of these cams that they act through rods and levers in a well-known-way to unseat the respective valves at proper times and hold them open the desired length of time. Each cam 45, 46 115 and 47 is made double, as shown in Figs. 7 and 8, for the purpose of reversing, and this is effected by the means best shown in these figures. The cams, as before stated, are 120 fixed on their respective shafts, and the 125 130

cam-shafts are mounted slidably longitudinally in their bearings, the gears on the shafts for driving them being splined so that the shafts may play through them. On 5 the end of each shaft is a loosely collared ring 48, coupled by links 49 to the shorter arm of a reversing elbow-lever 50, for the upper cam-shaft, and of a similar lever 51, for the lower cam-shaft. The cams are 10 double, and by shifting them either end portion may be brought to act on the valve through the intermediate mechanism. Or if moved so that the middle portion of the cam is at the working point, the valves will 15 not be operated and the engine will stop. For example, respecting the cams 45 and 46, as seen in Fig. 8; the parts v operate the valves for going ahead; the parts v^1 operate the valves when the engine is reversed, and 20 the part x , at the middle, is so cut away that when it is brought to the operating point the cam is inert. The cam 47, on the shaft 44, is mounted on a separate shaft in order that it may have or perform another function 25 in addition to that of operating the air inlet-valve 8, for running ahead or backward. It is desirable to construct this cam so that it will allow the air inlet-valve to close at different points in the stroke of the 30 piston, in whichever direction the engine may be running. Hence the cam has (in addition to the two operative portions v , v^1 , and the inoperative or inert middle portion x) the operative portion made up of a plurality 35 of sections u , so set as to become inactive successively at different points in the revolution of the cam-shaft, thus acting to open the valve at the same point in the stroke but to hold it open for different periods 40 of time, thereby enabling the engineer to control the amount of air held in the outer end of the cylinder for compression. The cam may have, and preferably will have, at w in Fig. 7, an enlargement of the 45 section of the cam which is operative when the engine is going ahead at full speed; this enlargement opens the air inlet-valve to a greater extent than the other sections. The reversing levers play in the usual guides 52, 50 and have the usual locking devices for holding them in the positions set. The upper lever 50 is set in one of three positions, but the lower lever 51 may be set to put either 55 of the sections u of cam 47, into the proper position to actuate the valve. The reversing lever 50 is coupled loosely to the lever 51 in such a manner that when the engine is reversed through the lever 50, the cam 47 will also be reversed, but play will be allowed 60 for shifting the cam 47 independently for regulating the speed. This coupling device for operatively connecting the levers 50 and 51 may be of any kind, but that shown in Fig. 10 will suffice and this will 65 now be described. The lever 50 is secured

to a journal 50^a, which is prolonged to form the shaft 54. The lever 51 is secured to a journal 51^a, aligned with the journal 50^a. These journals have bearings in the frame 52. On the end of the journal 50^a is a pin 70 50^b, which engages a recess or way 51^b formed in the upper end of the journal 51^a. The pin couples the two journals together but allows a movement of the lever 51 which is independent of the lever 50. By 75 this construction the speed-regulating cam 47 will always be automatically placed with the part x thereof at the operative position when the engine is reversed in either direction, no matter what may be the speed of 80 the engine when the reversing lever is shifted, leaving the after regulation of the cam 47 to be effected by the lever 51. This interlocking of the levers prevents any error 85 in adjusting the speed-controlling cams by permitting the speed-regulating lever 51 to shift the cams 47 in the proper direction only, in whichever direction the engine may be running.

The controller C¹, which is shown somewhat diagrammatically in Fig. 9, is inclosed in a casing 53, its contact arm being carried by the upright shaft 41. In reversing, the contacts are shifted by a switch in the casing 53. This switch is actuated by means seen best, perhaps, in Fig. 7. The fulcrum point y of the lever 50 carries an upright shaft 54, on the upper end of which is a crank 55, which is connected by a link 56 with a crank-arm 57. This arm 57 is fixed on a short shaft, which extends up into the casing and carries the switch arm. Obviously whenever the reversing lever is operated this switch-arm will be shifted. As such a controller and switch for reversing is an electrical construction within the knowledge of any electrical engineer, it will only be necessary to say, with especial reference to Fig. 9, that the controller C¹ has two sets of contacts i , one set being put in the igniting circuit with the wires c^1 and c^2 when going ahead, and the other when the engine is reversed. This is effected by the switch controlled by the reversing lever. The contact-arm j of the controller plays over both sets of contacts. If there is but one engine there will be but two of these contacts in the controller, one for operating when going ahead and one for operating when the engine is reversed.

It will be understood that any suitable combustible and vaporizable fluid or gas may be used for mixing with the compressed air to produce an explosive charge; and the terms carbureter and carbureting as herein employed are not intended to limit, to the use of a volatile hydrocarbon for mixing with the air although such a hydrocarbon will usually be employed. Of course gas, alcohol, and the like may be employed. It 130

will also be understood that the air compressed at each stroke in the cylinder below the piston, is fully compressed, and the charge formed thereof is not afterward further compressed. Also, this fully compressed air is carbureted on its way to the combustion chamber of the engine.

In Fig. 6 a throttle valve T is shown in the pipe 13 for the purpose of cutting off the supply of the explosive mixture to the engine.

In order that the terms "outer end" and "inner end" as herein applied to the cylinder of the cylinders, may be clearly understood, it will be proper to explain that by "outer end" is meant that end of the cylinder which as herein shown, is presented toward the crank; and by "inner end" is meant the end farthest from the crank, with which the combustion chamber is connected. In the present construction, where the engines are upright or vertical, the "outer ends" of the cylinders are the lower ends, and the pistons on their outstrokes, move toward the cranks.

Having thus described my invention, I claim—

1. An internal combustion engine, having a combustion chamber at one side of the piston, a closed air-compressing chamber at the other side of the piston, wherein air is fully compressed by the piston, an air-admission valve which opens inwardly, means actuated by the engine for opening said valve, and for holding the same open, as desired, during some part of the compressing stroke of the piston, a carbureter, a conduit connecting said carbureter with said compressing chamber, and a conduit connecting said carbureter with the combustion chamber of the engine.

2. An internal combustion engine, having a combustion chamber at one side of the piston, a closed air compressing chamber at the other side of the piston, wherein air is fully compressed by the piston, an air-admission valve which opens inwardly, means actuated by the engine for opening said valve and for holding the same open, as desired, during some part of the compressing stroke of the piston, a conduit which leads the compressed air to the combustion chamber of the engine, a valve at the engine controlling the flow of air from the cylinder to said conduit, said valve opening outwardly, a spring behind said valve to hold it closed, means for carbureting the compressed air on its way to a combustion chamber of the engine, a valve controlling the admission of the carbureted charge to the said chamber, and means for igniting the charge in said chamber.

3. An internal combustion engine, having a combustion chamber at one side of the piston, a closed air-compressing chamber at the other side of the piston, wherein air is fully

compressed by the piston, an air-admission puppet-valve 8, opening inwardly, a spring 9 on the stem of said valve for closing it, mechanism actuated by the engine and adapted for opening and holding open said valve during a variable portion of the compressing stroke of the piston in order to regulate the volume of air compressed, a conduit for conveying the compressed air from the compression chamber, a puppet-valve 11 at the engine and controlling the admission of the compressed air to said conduit, said valve opening from the cylinder, and a spring 12, which holds said valve closed yieldingly.

4. An internal combustion engine, having a supplementary combustion chamber, means for supplying thereto the explosive mixture, a main combustion chamber, a valve controlling the flow of gases from the supplementary to the main combustion chamber, said valve opening to the latter, means for balancing said valve, electrical igniters, one in each of said combustion chambers, and automatic means for switching the supply of electric energy from one of said igniters to the other, as predetermined.

5. An internal combustion engine, having a supplementary combustion chamber, means for supplying thereto the explosive mixture, electrical means for igniting the charge in the said supplementary chamber, a main combustion chamber open to the engine cylinder, a valve controlling the passage connecting one combustion chamber with the other, said valve opening to the main combustion chamber, automatic means for opening said valves at proper times, electrical means for igniting the charge in the main combustion chamber, automatic electrical means for switching out the igniting means for the main combustion chamber when the engine stops and switching in the igniting means for the supplementary combustion chamber, and automatic electrical means for switching in a separate source of electrical supply for igniting when the engine stops.

6. An internal combustion engine, having a supplementary combustion chamber 15, a main combustion chamber 20, an intermediate chamber 18 connected by a passage with chamber 15, a piston-chamber 30 above the chamber 18, a balance piston 29 in the latter chamber, a stemmed valve 19 between the chambers 18 and 20, and controlling the flow of gases from the former to the latter, the balance piston 29 being fixed on the stem of the valve 19, means for admitting compressed air to the chamber 30 under the piston 29 to balance the valve 19, electrical igniters, one in each combustion chamber, means for supplying electric energy to said igniters, means for automatically switching the supply from the said igniters alternately in a predetermined manner, and means for

supplying a compressed explosive charge to the chamber 15.

7. An internal combustion engine, having means for compressing air in its cylinder 15 on the outstroke, means for regulating the amount of air left in the outer end of the cylinder at each revolution, for compressing, means for carbureting the compressed air, means for carrying the carbureted air to a 10 combustion chamber of the engine, and means for igniting the same.

8. An internal combustion engine, having a cylinder with a closed chamber at its outer end in which air is compressed at each out- 15 stroke of the piston, a valve controlling the air-inlet to said chamber, regulable means actuated by the engine for opening said valve, an outlet conduit for carrying away the compressed air, a non-return valve con- 20 trolling the said outlet conduit, means for carbureting the compressed air, a non-return valve controlling the compressed air-conduit and provided with a screw to close the valve and hold it closed when desired, means for 25 supplying the compressed explosive mixture to a combustion chamber of the engine, and means for igniting it in said chamber.

9. The combination with an explosive engine, of a charge holding chamber and a 30 pressure chamber, a valve controlling communication between the charge holding chamber and the engine and having a piston in the pressure chamber, means for delivering charges to the charge holding chamber, 35 and a conduit delivering fluid under pressure from the delivering means to the pressure chamber.

10. The combination with an explosive engine having an explosion chamber and an 40 air compressor, of a charge holding chamber communicating with the explosion chamber, a pressure chamber associated with the charge holding chamber, a carbureter connected to the charge holding chamber, an 45 air pipe for delivering air from the compressor to the carbureter, a valve controlling the communication between the charge holding chamber and the explosion chamber and having a piston operating in the pressure

chamber, and means for conducting air 50 from the air pipe to the compressor chamber.

11. The combination with an explosive engine having an internal explosion chamber, of means for feeding charges to the explosion chamber including a charge holding 55 chamber, and means for exploding an engine starting charge in the charge holding chamber and for exploding charges successively thereafter in the explosion chamber.

12. The combination with an explosive 60 engine having an internal explosion chamber, of means for feeding charges to the explosion chamber, including a charge holding chamber, a valve controlling the communication between the charge holding and explosion chambers, means for exploding an engine starting charge in the charge holding chamber, and for exploding charges successively 65 in the explosion chamber after the engine is started, said valve being automatically opened by the explosion of an engine starting charge, and means operated by the engine for periodically operating the valve. 70

13. The combination with an engine comprising a cylinder and a piston operating 75 therein, said piston forming an explosion chamber on one side and an air compressor on the other side, a charge holding chamber communicating with the explosion chamber, a conduit connecting the air compressor 80 chamber with the charge holding chamber, means for exploding charges either in the charge holding chamber or in the explosion chamber, a valve controlling the communication between the charge holding and explosion chamber, said valve being automatically 85 opened by the explosion of charges in the charge holding chamber, and means operated by the engine for periodically opening the valve. 90

In witness whereof I have hereunto signed my name this 28th day of September, 1904, in the presence of two subscribing witnesses.

JOSEPH ALVAH SCOTT.

Witnesses:

HENRY CONNETT,
WILLIAM J. FIRTH.
